UNITED STATES PATENT OFFICE.

ALPHEUS A. KINNEY, OF PARIS, NEBRASKA.

WINDMILL.

SPECIFICATION forming part of Letters Patent No. 352,875, dated November 16, 1886.

Application filed July 2, 1886. Serial No. 206,925. (No model.)

To all whom it may concern:

Be it known that I, ALPHEUS A. KINNEY, a citizen of the United States, and a resident of Paris, in the county of Sherman and State of Nebraska, have invented certain new and useful Improvements in Windmills; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view of my improved windmill. Fig. 2 is a vertical sectional view of the same. Fig. 3 is a rear view of the wheel. Fig. 4 is a front view of the same. Fig. 5 is a perspective view of one section of the wheel. Fig. 6 is a top view of the mill; 20 and Fig. 7 is an enlarged detail view of the governing rod and sleeve, the sleeve being partly broken away.

Similar letters of reference indicate corresponding parts in all the figures. 25 My invention has relation to that class of windmills having a wheel journaled to revolve in a vertical plane, and having the vanes arranged in sections or groups pivoted to swing in planes at angles to the plane of the wheel; 30 and it consists in the improved construction and combination of parts of the same, as hereinafter more fully described and claimed.

In the accompanying drawings, the letter A indicates the frame or tower of the mill, which 35 tower is of the construction usually found in windmills of this class, and the upper end of this tower is provided with a platform, B, from the center of which project two upright posts, C C, which are connected at their upper 40 ends by a plate or casting, D, formed with upwardly-projecting pairs of lips E E, arranged in a circle around a central aperture, rollers G being journaled between the said lips, forming a rest for the turn-table H, to which the 45 wheel and guide-vane are attached.

The turn-table H is provided with a downwardly-projecting central sleeve, I, which projects through the central perforation in the casting supporting the turn-table, the sleeve 50 being journaled in the said perforation, and the lower end of the sleeve is journaled in a bearing, J, secured between the upright posts.

The turn-table is provided with a laterally-projecting hollow arm or bearing, K, for the wheel-shaft L, and with a diametrically opposite-projecting arm, M, to which the guide-vane N is secured, and an arched piece, O, extends from the inner end of the bearing for the shaft to the arm carrying the vane, extending over the upper open end of the sleeve of the turn-table, having a bearing, P, concentric with the said sleeve. The inner end of the wheel-shaft is formed into a crank, Q, and a short pitman, R, is pivoted to this crank and to the pump-rod S, the upper end of the said rod sliding in the bearing of the arched piece. The wheel is composed of a hub or spider, T, having a number of radiating arms, U, formed with perforated lips V V at their ends, in which lips the trunnions W W, at the ends of transverse bars X, are journaled.

The inclined vanes Y are secured in inclined notches Z in the rear side of these transverse bars, and are connected at the inner ends by a transverse notched piece, A', and the forward 75 vanes, B', are secured in notches C' in the transverse bars and pieces, in planes at right angles to the faces of the bars.

Blocks D' are pivoted with trunnions E' at their ends between the arms, near the inner 80 ends of the same, and are formed with transverse perforations F' at their middles, through which perforations pass rods G', having arms H' pivoted to their outer ends, the said arms being pivoted at their outer ends to the cross-bars of the vane-sections, slightly above the line of the trunnions of the same. The inner ends of the rods in the pivoted blocks are pivoted to a sleeve, I', sliding upon the wheel-shaft, and this sleeve is formed with a circumferential 90 groove, J', in which fits a collar, K', to which two rods, L' L', are secured, with their outer ends sliding in horizontal bearings M' M' at the sides of the bearing for the shaft. The inner ends of these rods are pivoted to the ends 95 of a bifurcated bell-crank, N', pivoted upon the inner side of the portion of the arched piece nearest to the guide-vane, and the upper end of a vertical rod, O', is pivoted to the other end of the bell-crank, passing down 100 through the sleeve of the turn-table. This sleeve is provided with a vertical slot, P', in one side, and a laterally-projecting headed bolt, Q', slides in this slot, having its headed

outer end sliding in a groove, R', in the inner side of a ring or collar, S', sliding upon the sleeve and having the sleeve turning within it. The upper end of a bar, T', is secured to this collar, and the lower end of the bar is pivoted to one end of a lever, U', pivoted upon the side of the tower, and a bar, V', is pivoted with its upper end to the other end of this lever, and has its lower end pivoted to a lever, W', pivoted at one end to one of the corner posts of the tower, and having a weight, X', sliding upon it outside of the pivotal point of the vertical bar.

It will be seen that when the wheel is revolved the crank upon the wheel-shaft will reciprocate the pitman and the pump-rod, the upper end of which reciprocates in the bearing in the arched piece, and the lower end of the pump-rod may be directly connected to the piston-rod of a pump, or the reciprocating motion of the pump-rod may be conveyed to a more distant place or be converted into a rotary motion, as desired. When the force of the wind increases, the wheel-sections will have their outer portions tilted rearward, which will cause the arms pivoted to them to tilt the outer ends of the rods in the pivoted blocks forward, sliding the sleeve upon the shaft inward and depressing the rod in the sleeve, which will depress the collar upon the sleeve and the bar attached to it, causing the lower vertical bar to be raised, raising the weight upon the lever, and when the force of the wind again decreases the weight will depress the lever and reverse the former motion, tilting the wheel-sections to offer their full surface to the wind, the sections when tilted back only offering a slight surface for the action of the wind. The forward set of vanes in the wheel will cut the wind and direct it toward the rear inclined set of vanes, and this arrangement will be found of a great advantage in a strong wind, the vanes cutting and dividing the force of the wind and directing it against the inclined vanes.

The wheel-sections may be set at any desired angle by moving the lever by hand, and after moving the lever, either raising or lowering it, as desired, the weight may be adjusted so as to hold the lever, and consequently the wheel-sections, in the adjusted position until

the wind either increases or decreases in force, when the lever will act in the same manner as before described.

The governing-rod, having the laterally-projecting bolt upon its lower end sliding in the vertical slot and in the groove in the inner side of the sliding collar, will admit of the collar and rod being raised and lowered, and also of the sleeve being turned within the collar, the operation of one interfering in no manner with the operation of the other.

Having thus described my invention, I claim and desire to secure by Letters Patent of the United States—

1. In a windmill, the combination of a frame and two sets of vanes, the front set being at right angles to the face of the wheel, and the rear set being at an angle to the front set and having their front edges in a line with the rear edges of the front set.

2. In a windmill, the combination of radiating arms upon the wheel-shaft, wheel-sections of vanes secured to cross-bars provided with trunnions at their ends pivoted in lips upon the arms, a sliding adjusting-sleeve upon the wheel-shaft, blocks pivoted at their ends between the inner ends of the radiating arms and having rods sliding in perforations in the middles of the blocks and pivoted to the sleeve with their inner ends, and arms pivoted with their inner ends to the outer ends of the rods and with their outer ends to the outer portions of the wheel-sections, as and for the purpose shown and set forth.

3. In a windmill having a downwardly-projecting sleeve journaled in the supporting frame and formed with a vertical slot in its side, the combination of a governing-rod having a headed bolt projecting through and sliding in the slot, a collar upon the sleeve and having a groove in its inner side for the head of the bolt, and a handle for sliding it up and down upon the sleeve, as and for the purpose shown and set forth.

In testimony that I claim the foregoing as my own I have hereunto affixed my signature in presence of two witnesses.

ALPHEUS A. KINNEY.
